ILLUMINATED PUMP DIAL

Filed June 27, 1930

UNITED STATES PATENT OFFICE

CHARLES W. HOFFRITZ, OF LOS ANGELES, CALIFORNIA

ILLUMINATED PUMP DIAL

Application filed June 27, 1930. Serial No. 464,413.

This invention relates to improvements in gasolene pumps and more particularly to the dial thereon.

One of the objects of the present invention is to provide a simple, efficient and inexpensive pump dial which is rendered visible at great distances at night by means of neon-illuminated characters displayed upon the surface of the dial.

10 A further object of the present invention is to provide a gasolene pump dial with means designed to effectively seal the various assembled parts thereof against the entrance of any of the fumes originating from the gasolene, to prevent contamination of the neon gas by the gasolene fumes, and to safeguard the electrical connections as well.

20 Another object of this invention is to provide a source of colored illumination for the display dial of a gasolene pump and the like wherein use is made of concealed illumination parts so that only the translucent letters, figures or characters on the dial will be illuminated.

25 A final object thereof is to provide, in a gasolene pump means for securing a dial panel interiorly of the dial case, the panel having sand-blasted characters, designed to be illuminated by means of a hidden neon tube, the light rays emanating from the neon tube passing through the peripheral edge only of the dial panel and reaching the sand-blasted characters to render the same highly illuminated at night.

30 With the above and other objects in view my invention consists in the combination, arrangement and details of construction disclosed in the drawing and specification, and then more particularly pointed out in the appended claims.

In the drawing, wherein similar reference characters designate similar parts throughout the respective views,

45 Figure 1 is a vertical sectional elevation of the dial section of a gasolene pump,

Figure 2 is a vertical section of the device taken at right angles to Figure 1,

50 Figure 3 is a fragmental front elevation of the dial panel,

Referring to the drawing, 10 designates a

cover plate formed with a major cylindrical housing N. The interior of a transformer containing box 14 is designated 11 which is formed hollow. The top section of the box 14 has a thickened web 13 at the point where it is desired to secure fasteners thereinto to secure the cover plate in correct position against the box 14. In the box 14 is mounted the conventional transformer 15 of approved design and construction, which is formed concentrically with the cylindrical housing N with an annular portion 16 approximately of the same diameter as the housing N. In the housing N is operatively fitted a glass or other transparent front panel 17, designed to be retained therein by means of the split contractible ring 24 or the like.

The display dial panel is designated 33 and is preferably made of glass. This display panel will have the desired characters herein-after to be described sandblasted thereupon so as to be rendered translucent while the main background of this display dial panel will be opaque. The panel 33 is held into a pressed engagement so as to be snugly squeezed between a pair of annular resilient packing rings or gaskets 18 and 31, these gaskets overlying opposite faces of the marginal or rim portion of the dial panel 33. In this manner, it will be observed, the housing N will have its interior surface 21 completely and effectively sealed against the possibility of intermixture of the fumes resulting from the gasolene contained in the pump proper with the neon gas or any derivatives thereof that may be present in the hollow interior 11 of the transformer box 14, or which might be found in the housing N itself. This is an important feature of my invention since the neon tube 40 must be guarded against all foreign influences.

The cover plate 10 is attached removably to the open end of the transformer box 14 by means of suitable screws or other fasteners 19, which penetrate the cover plate, and a continuous endless packing ring or gasket 39 having the same shape and outline as the invention itself. The gasket 39 is interposed between the cover plate 10 and the front edge of the box 14, and between the cover plate

and a back plate 25, so that the fasteners 19 will enter the thickened portion 13 of the box 14 to draw the cover plate tightly against this box, at the upper part of the box 14, and so that other fasteners 36 will draw together the cover plate, packing 39, and back plate 25, after passing through these parts. The packing strip 39 also serves to completely seal the neon tube 40 from interferences caused by foreign matter entering the chamber in which the tube is positioned. M designates the inner circumference of the annular portion 16.

The back plate 25 is formed concentrically with the portion 16 but diametrically opposite to the latter with a lateral abutment 29 against which the packing strip 18 contacts, when the housing N, the front cover plate and rear cover plate are all drawn together into a clamped unit. The front glass panel 17 bears against the annular ledge 32 formed upon the front cover plate. The back plate 25 is formed with a groove 11' in which is adapted to extend the cylindrical portion of the neon tube 40 in such a manner as to lie opposite the peripheral edge of the dial panel 33, as shown in Figure 2, and so as also to be in the same plane with this dial panel.

In Figure 3 the manner of inscriptions borne and displayed by the dial panel is disclosed. 35 designates the translucent characters preferably sand-blasted upon the face of the display dial panel 33. The neon tube 40 is formed with the parallel spaced branches or offsets 41, 42 which extend beyond the confines of the packing strips 18 and 31 into the transformer box 14, as shown in Figure 1. The branches 41, 42 of the neon tube 40 then spread outwardly and form the oppositely extending bends 43, 44 which connect directly into the transformer, in a manner known to those skilled in the art.

At 51, on the dial panel 33 will be displayed in a translucent manner the legend "Gallons". Midway between the upper and lower dead center positions of the panel will be displayed translucently the legend "1/4 Gallon" in any effective manner. At 52 this last-named legend appears. At the lower dead center position is displayed translucently the legend "1/2" in conjunction with the inscription "Gallons" in any effective manner, as at 52a. Diametrically opposite to the legend "1/4 Gallon" is displayed translucently the legend "3/4 Gallons" in any effective manner. 50 designates the pointer which indicates movably the particular quantity of gasoline being pumped. A designates by means of the circumferentially extending series of arrows the lines of rays of colored light which emanate from the neon tube 40, and which immediately penetrate through the dial panel 33 edgewise or peripherally thereof and it will be seen that the rays of light A pass radially towards the center of

the panel and hence the light, the moment same traverses the series of characters 35 will conspicuously illuminate the same in any color produced by the bombardment of the electrodes connected in the conventional manner to the neon tube 40 (not shown). As a result of this arrangement of the neon tube in a manner that causes it to encircle the peripheral edge only of the display panel 33, and as a result of the opaqueness of the background of this panel, the characters 35 will stand out at night in bold relief so as to be readable from great distances. The source of colored light, or the neon tube 40 will, in no manner, be observed from outside the dial. And the neon tube will be so effectively sealed in its compartment by the various compressible gaskets or packing rings as to exclude foreign particles or substances from entering the same, as it is known that gasoline fumes are volatile enough to find their way into the tiniest of crevices.

From the foregoing it will be seen that I produce an illuminated pump dial which will display the usual dial characters at night with an intensity of luminosity that assures correct readings to be had at great distance from the position of the gasoline pump itself. I do not intend to limit myself to the exact details of construction herein set forth but claim all variations falling within the purview of the appended claims.

What I desire to claim and secure by Letters Patent is:—

1. In combination with display apparatus, a dial casing carried thereby, a transparent cover for the dial, a glass dial having a series of translucent characters thereon displayed thru the transparent cover, a neon tube arranged in the casing concentrically of said dial and diffusing light upon the dial so as to illuminate the characters thereof, a transformer case adjacent to the dial into which the neon tube extends, and a fluid-tight seal means rendering the separate parts of the dial, transformer, cover, and tube proof against entrance of moisture, air and the like.

2. A device of the kind described consisting of a display device having a dial case formed with an internal ledge of annular shape, a cover plate of circular formation having a transformer-containing box closing part at its upper end, a front glass panel fitted into the dial case, a rear cover plate formed upon the dial case whose lower part is clamped against the other cover plate, a packing strip interposed between the confronting parts of the secured ends of the two-cover plates, clamping means drawing the cover plates together, to render the dial casing fluid-tight, a display dial panel fitted into the dial case adjacent the glass panel, packing strips engaging both sides along the marginal edge of the dial panel and engaging respectively against the front and rear cover

plates, and a colored light-producing neon tube encircling the peripheral edge of the dial panel for diffusing light rays radially through the dial panel towards the center 5 thereof, said dial panel having a series of sand-blasted characters of translucent tendency displayed in an opaque background whereby the radial rays of colored light emanating from the neon tube may completely 10 illuminate said characters at night.

3. In a device of the kind described in combination a dial case, a cover plate for said dial case, the cover plate and dial case having marginal portions producing a housing, circular in cross-section, a circular neon tube disposed laterally of the circular housing and having a source of current supply outside the dial case, means for providing a fluid tight connection for the source of current 15 supply between the cover plate and the dial case, an opaque dial having translucent characters receiving rays of colored light peripherally of the dial from the neon tube, means producing a fluid tight seal between the cover 20 plate and the dial case, and means removably securing the cover plate upon the dial case.

4. In combination a circular dial case having a marginal web, a cover plate for the dial case also having a marginal web, the case web being formed with a semi-circular coextensive seat outside the case, the web of the cover plate also being formed with a coextensive semi-circular seat, the outermost 25 surfaces of the two webs being flat so as to be arranged in confronting relation, packing ring interposed so as to directly contact the webs to provide a fluid-tight seal for the circular chamber provided by both webs when joined together, means clamping the 30 cover plate removably against the packing strip and the dial case, a display device exposed to view thru the cover plate and having transparent characters thereon, and a circular neon tube lodged in the circular 35 chamber and diffusing light rays to illuminate directly the interior of the dial case and to indirectly illuminate the transparent characters of the display device.

5. In a device as described, a dial case, a 40 glass dial in said case having an opaque face on which appear translucent characters, neon means arranged peripherally of the dial for illuminating the same, and rubber gaskets interposed between the dial and adjacent 45 surfaces of the case to render a fluid tight seal between these parts.

6. As a new article of manufacture a circular case having an internal medial flange, a cover plate having a display opening, an 50 opaque glass dial carried by said case having visible translucent characters packing rings disposed between the peripheral surfaces of the cover plate and circular case, means for clamping the cover plate home 55 upon the case to provide a fluid tight con-

nection between cover and case, a circular neon tube seated within the case peripherally of the glass dial for illuminating the translucent characters thereon, and packing rings 60 clamped on opposite sides of the marginal portions of the dial to hold the latter in a fluid tight connection in the case.

7. As a new article of manufacture a box having an open end, a cover for said box, a circular dial case formed in a plane with said cover, the inner wall of the box being spaced away from the cover to provide a narrow channel communicating with the dial case, a cover plate formed in a plane with the inner 65 part of the inner wall of the box, the portion of the cover plate diametrically opposite the inner wall of the box being clamped against the side of the dial case, a glass dial positioned so as to project marginally into the narrow channel, a transformer in the box, and a circular neon tube surrounding the peripheral edge of the glass dial and having a connection to the transformer.

8. As a new article of manufacture a display device formed with a circular case having an internal medial flange, a cover plate, a glass dial carried by the case having translucent characters, the peripheral portions of said cover plate and circular case contacting in a manner to space the flange out of contact with the adjacent surface of the cover plate, packing rings clamped between the peripheral contacting surfaces of the cover plate and case, means for clamping the cover plate home upon the case to provide a fluid tight connection between cover plate and case, a circular neon tube seated between the case and the cover plate around the peripheral edge of the glass dial for illuminating the translucent characters, and packing rings flanking the dial, the internal flange of the case and the inner face of the cover plate respectively.

In witness whereof he has hereunder set 90 his hand this 8th day of January, 1930.

CHARLES W. HOFFRITZ.
